UNITED STATES PATENT OFFICE.

ROBERT LUNDELL, OF BROOKLYN, NEW YORK, ASSIGNOR TO THE JOHNSON-LUNDELL ELECTRIC COMPANY, OF NEW YORK, N. Y.

ELECTRIC RAILWAY.

SPECIFICATION forming part of Letters Patent No. 594,702, dated November 30, 1897.

Application filed August 24, 1896. Serial No. 603,723. (No model.) Patented in England September 17, 1896, No. 20,796.

To all whom it may concern:

Be it known that I, ROBERT LUNDELL, a citizen of the United States, residing at Brooklyn, in the county of Kings and State of New York, have made a new and useful Invention 5 in Electric Railways, of which the following is a specification, said invention having been patented in Great Britain, with my knowledge and consent, on the 17th day of September, 1896, and numbered 20,796.

My invention is directed especially to that type of electric railways known in the art as "surface trolleys," in which the electrical current is conveyed to the propelling-motor by 15 sectional conductors or contacts made temporarily alive beneath a car only while it travels over them; and its object is to make sure of such temporary connections between the sectional conductors and the current feeder 20 or main and of their disconnection therefrom as the propelled car passes on over the route, so as to thereby insure certainty of action and also safety to persons and animals. This object is fully accomplished by the means illustrated 25 in the accompanying drawings and hereinafter described, the especial features of novelty of my invention being particularly pointed out in the claims at the end of this specification.

Figure 1 of the drawings illustrates, diagrammatically, an electric railway embodying my invention; and Fig. 2 is a cross-sectional view of the road-bed, tram-rails, and sectional trolley-conductors, illustrating also one of the 35 contact-buttons fixed in the road-bed.

Referring now to the drawings in detail, W W represent the wheels of a car carrying a propelling electric motor M of any well-known type and the usual operating or controlling 40 switch Sw, operatively connected to a rheostat, and a small storage battery B, preferably of low voltage.

R and R' represent the track or tram rails, and Sc' Sc², Sc³ Sc⁴, Sc⁵ Sc⁶ pairs of sectional 45 trolley conductors or rails embedded in the surface of the road-bed parallel with the rails R R', as clearly shown. These sectional trolley-conductors are preferably of T-rail form, as shown, and are firmly secured to the cross-ties in such manner as to leave spaces of only about one or one and one-half inches in breadth

between them and the rails R R', their surface width and strength being such as to offer to wagon-wheels sufficient resistance to prevent the forming of gutters near the tram-rails, as is now the case in existing lines of street-railways.

T T and Tr Tr are trolley-wheels, preferably of steel and of V shape, so that they will readily cut through ice or mud and remain 60 always in electrical contact with the sectional trolley-conductors as they pass thereover. These trolley-wheels are electrically connected together and to the battery B by conductors, as shown.

65 Is a conducting trolley-shoe of well-known form, carried by the car and electrically connected to the motor M and adapted to bridge and bear successively upon conducting contact-buttons B' B² B³, &c., located, preferably, at the middle of the road-bed, one between each pair of sectional trolley-conductors Sc' Sc², &c. Each of these contact-buttons is connected to a branch feeder extending into a switch-box, (not shown,) wherein 70 are located two pairs of switching-contacts, one pair of said contacts being adapted to connect the normally open branch feeder to the positive or plus main feeder, and the other pair to in like manner connect one line of the 75 sectional trolley-conductors Sc², Sc³, or Sc⁶ to the negative feeder or main, M', M², and M³ being switching-magnets the cores or armatures of which carry movable switching-contacts, as shown. The other sectional trolley- 80 conductors Sc' Sc³ Sc⁵, &c., it will be noted, are permanently connected to the tram-rails R R' through the switch-magnets M' M² M³, &c., the circuit connections between these sectional trolley-conductors, the trolley-wheels Tr Tr, and system of conductors on the car being such that the battery B, when connected in circuit, will energize the switch-magnets in sequence as the car advances.

90 The operation is as follows: Suppose the voltage on the main feeders to be five hundred and that of the battery B to be ten, and that the winding and resistance of the switch-magnets is such that they will operate for, say, fifteen amperes of current. On closing 100 the switch Sw current flows from the plus pole of the battery B in a direction reverse to the

- arrow to the switch and to ear-wheel W to ground or tram rails R R', which are bonded together, thence through the core of magnet M² to sectional trolley-conductor Sc³, trolley-wheels Tr Tr, back to the minus pole or battery B. This energizes the magnet M² and causes its core or armature to actuate the movable switching-contacts, so as to close the circuit from the power-house generator through the motor and battery on board the car by way of the positive and negative mains or feeders, as follows: by way of the plus or positive main in the direction of arrow to the switch-contacts to branch feeder, thence to contact-button B², trolley-shoe S to motor M and switch S_w, where the current divides, one part flowing through the magnet-coil M², as before, to the minus feeder or main and the other part charging the battery B and passing thence to trolley-wheels T T, sectional rail Sc⁴, and switch-contacts on the right to the minus feeder also. The instant that the trolley-wheel Tr comes into contact with the next sectional trolley-rail Sc⁵ in advance less charging-current will flow through the battery inasmuch as there are now two switch-magnets M² and M³ in parallel circuit, the resistance of the magnet-circuit being only one-half as much as before.
- It will be apparent upon examination of the circuit operating the switching-magnets that no leakage-currents can hold the magnets closed after a car has passed. If there is any surface leakage at all, this will take place between one of the buttons and the sectional rails. Leakage-current from the buttons to sectional rails Sc² Sc⁴ Sc⁶ will go directly through the switching-contacts to the minus main without affecting the magnet-coils, and the leakage-current from buttons to the other sectional rails Sc' Sc³ Sc⁵ will pass through the magnet-coils in the wrong direction (reverse to arrows) before it can find its way to the minus main. This leakage will cause the magnets to open quickly.
- What I claim, and desire to secure by Letters Patent of the United States, is—
1. An electric-railway system provided with a current feeder or main, normally open branch feeders, conducting contact-buttons, and sectional trolley rails or conductors, in combination with electromagnetic switching devices provided with pairs of switching-contacts and circuit-conductors whereby any surface leaking current to the switching-magnets from the current feeder or main after a car has passed a given switching-magnet will always be conveyed therethrough in a direction the reverse of that taken by the working current while the car or vehicle is being propelled over the route, substantially as described.
  2. In an electric-railway system a current feeder or main, a series of branch feeders running from said current feeder or main to a series of conducting-contacts but normally open at points between said contacts and the

current feeder or main, in combination with two sets or lines of sectional trolley-conductors, one of which sets is operatively connected with normally open branch feeders running to a negative main or return circuit, the other set being connected to the coils of switching-electromagnets, the cores or armatures of which are provided with circuit-closing contacts for closing both sets of branch feeders and circuit connections between said contacts and the switching-electromagnets whereby the working current from the current feeder or main flows directly to the conducting trolley-shoe carried by a car and any leaking current from the current feeder or main to the switching-magnet after the car or vehicle has passed a given section will always enter the coils of such switching-magnet in a direction the reverse to that taken by the energizing or operating current, substantially as described.

3. In an electric-railway system positive and negative current feeders or mains, sets of normally open branch feeders running respectively to conducting contact-buttons and one set of sectional trolley-conductors, a second set of sectional trolley-conductors connected to switching-electromagnets, in combination with a conducting trolley-shoe operatively connected with a motor on board of a car or vehicle and two sets of trolley-wheels adapted to contact with the sectional trolley-conductors and circuit connections between said contacts and the switching-electromagnets whereby the working current passes directly from the positive-current main through a branch feeder to the motor on board of the car, and any surface leakage occurring after the passage of the car will always flow through the switching-magnets in a reverse direction to that taken by the operating-current, substantially as described.

4. In an electric-railway system, three sets of surface contacts, one set being connected to the positive or plus current main, the second to the negative or minus main or return and the third set connected to the track-rails through switching-electromagnets, substantially as described.

5. In an electric-railway system, two current feeders or mains, two lines or sets of sectional trolley-conductors arranged in pairs, in combination with a third line of contacts located between said lines, and circuit connections with switching-electromagnets for connecting the third line of contacts with the plus or positive current main and the two lines or sets of sectional conductors respectively with the negative feeder and the switching-electromagnets, said parts being so located with relation to each other that any surface leaking current to the switching-electromagnets from the current feeder or main after a car has passed a given magnet will always be conveyed therethrough in a direction the reverse of that taken by the working current while a car or vehicle is being pro-

pelled over the route, substantially as described.

6. An electric-railway system having a positive and a negative current feeder or main, 5 two sets of normally open branch feeders, one for each current feeder or main, two sets of sectional trolley-conductors arranged in pairs, contact buttons or plates one between each pair of sectional trolley-conductors, in 10 combination with an electromagnetic switching device provided with pairs of switching contacts and circuit-conductors for each button and pair of sectional trolley-conductors, and a trolley-shoe carried by a car or vehicle 15 and adapted to span the distance between successive pairs of contact buttons or plates, together with a switch-operating battery and a propelling-motor carried by a car, said parts being so located with relation to each other 20 so that the operating-current passes directly from the positive-current feeder or main to and through the trolley-shoe and the motor on board of the car without affecting any switch-controlling magnets and also that any 25 surface leakage which enters a switching-magnet after a car or vehicle has passed such magnet will always flow through the coils

thereof in a direction the reverse to that taken by the energizing-current, substantially as described.

7. In an electric-railway system, a line of track-rails; positive and negative current feeders or mains; three sets of sectional contacts or conductors located between the track-rails, one set being electrically connected to 30 normally open branch feeders running to the positive-current feeder or main, the second set connected to normally open branch feeders running to the negative feeder or main, and the third set connected through the elec- 35 tromagnets of the switching devices with the track-rails, in combination with a trolley-shoe carried by a car and adapted to bridge adjacent pairs of contacts of one set and having 40 electrical connection with a switch-operating battery and a propelling-motor carried also on the car, substantially as described. 45

In testimony whereof I have hereunto subscribed my name this 22d day of August, 1896.

ROBERT LUNDELL.
